UNITED STATES PATENT OFFICE.

DANIEL W. AMOS, OF SAXTON, PENNSYLVANIA.

STEAM-ENGINE.

SPECIFICATION forming part of Letters Patent No. 311,703, dated February 3, 1885.

Application filed June 12, 1884. (Model.)

To all whom it may concern:

Be it known that I, DANIEL W. AMOS, a citizen of the United States, residing at Saxton, in the county of Bedford and State of Pennsylvania, have invented certain new and useful Improvements in Steam-Engines; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a side view. Fig. 2 is a plan view. Fig. 3 is a vertical sectional view. Fig. 4 is a transverse sectional view of the same, and Figs. 5 and 6 are detail views.

The invention relates to oscillating steam-engines, and its novel and useful feature is the making of the ports of the cylinder open on the convex face of a cylindrical segment, the said segment being situated vertically above, and secured to, the cylinder, and having the center of its arc coincident with the central transverse line of the trunnions upon which the cylinder oscillates. The ports of the steam-chest which are vertically above the cylinder, open on a concave face fitting accurately over the convex surface of the segment, and are so placed that the cylinder will successively take steam and exhaust from each end. The lower concave surface of the steam-chest is kept steam-tight with the convex surface of the segment (without producing too much friction) by means of leaf-springs situated on the upper surface of the steam-chest and controlled by screws which engage in uprights rising from the bed of the engine.

In the accompanying drawings, A represents the bed of the engine, having fixed thereto proper bearings for the trunnions *b b* of the cylinder B, the said trunnions being somewhat nearer the front end of the cylinder than to the rear end, so as to counterbalance the weight of the piston-rod C.

D is the crank-shaft of the engine, turning in proper bearings fixed to the bed A, connected with the piston-rod C by the crank *d*, and having properly attached the fly-wheel *c'*.

E is the segment of a cylinder fixed to the

steam-cylinder B, vertically above the same, or cast in one piece with it. The upper surface, *e*, of the said segment is made on the arc of a circle the center of which is coincident with the central longitudinal line of the trunnions *b b*.

F F' are the ports from the front and rear ends of the cylinder, respectively. These ports open at the points *f* and *f'* on the convex surface of the segment.

G G are equal and similar uprights standing from the bed of the engine at opposite points on each side of the cylinder B, the upper ends of which are flattened and extended horizontally frontward and backward, and have passing through said extensions, on each side, the screws *g g*, &c., which bind the steam-chest on the uprights and bring its concave lower surface to bear on the convex upper surface of the segment E.

H is the steam-chest, the lower concave surface, *h*, of which fits on the upper convex surface, *e*, of the segment E, and provided with the front and rear steam-ports, *h* and *h'*, respectively, and the exhaust-port *h''*, situated between and equally distant from both.

I I are leaf-springs resting on top of the steam-chest, on each side of the same, and having their concavity downward. Each leaf-spring *I* has passing through its center the screw *i*, which enters the top of an upright, *G*, and serves to depress the spring, and consequently the steam-chest, on which the spring rests, so as to bring the concave surface *h* of said chest into close contact with the convex surface *e* of the segment E and make them steam-tight without causing too much friction, as the springs will give sufficiently to allow the segment and attached cylinder to oscillate.

The operation of the engine is sufficiently evident from the description, for as the front port, *F*, of the cylinder oscillates under the port *h''* of the steam-chest it will exhaust into the same, the rear port, *F'*, at the same time taking steam from the port *h'* of the steam-chest. Any wear between the faces *h* and *e* is easily remedied by means of the screws *i i* and leaf-springs *I I*.

Having thus fully described my invention, what I claim as new, and desire to secure by Letters Patent, is—

1. In an oscillating steam-engine, the com-

bination, with the cylinder B, segment E, up-
rights G G, and steam-chest H, of the springs
I I and screws i i, substantially as specified.

2. An oscillating steam-engine having its
5 cylinder provided on its upper side with a
fixed segment, in combination with a steam-
chest having an engaging concave face, and
provided with springs adapted to keep the said
cylinder pressed down upon the said segment,
10 substantially as specified.

3. The combination, with the frame supporting
the steam-cylinder having the vertical
standards, of the steam-cylinder having the
15 segmental portion, the steam-chest, springs
for pressing the steam-chest in the direction
of the cylinder, and means for connecting the

chest with the said standards, substantially as
specified.

4. The combination, with the steam-cylinder
having the segmental portion and means 20
for supporting the same, of a steam-chest pro-
vided with spring-engaging devices, and
means of adjusting the tension of the spring,
whereby the said steam-chest may be kept in
engagement with the segmental portion of the 25
cylinder, substantially as specified.

In testimony whereof I affix my signature in
presence of two witnesses.

D. W. AMOS.
